DUPLICATING MACHINE

Willis A. Kropf, River Forest, Ill., assignor to
 Victor Adding Machine Company, Chicago, Ill.,
 a corporation of Illinois

Application May 31, 1940, Serial No. 338,100

12 Claims. (Cl. 101—132)

This invention relates to improvements in duplicating machines and in particular to the mechanisms for driving rotary drums and for feeding copy sheets so as to assure accurate registration of the copy sheets with the master copies.

One of the objects of the invention is to provide a novel driving mechanism for a rotary duplicating drum which will intermittently rotate the drum between positions at which copy sheets are fed to the drum.

Another object of the invention is to provide in a duplicating machine a margin stop on the drum of the machine and a mechanism for causing the drum to stop rotating to permit a copy sheet to be fed to the margin stop, while the primary driving means for the drum continues to rotate.

Another object of the invention is to provide gearless means for intermittently rotating a duplicating drum combined with a continuously operating driving means therefor.

Another object of the invention is to provide an automatic feed of copy sheets to a margin stop on an intermittently driven duplicating drum.

Various other objects and advantages of the invention will be described specifically or will become apparent from a perusal of this specification.

In the drawings, Fig. 1 is a sectional view on the line 1—1 of Fig. 3 of a machine made in accordance with my invention.

Fig. 2 is another sectional view on the line 2—2 of Fig. 3.

Fig. 3 is a view partly in elevation and partly in section along the irregular line 3—3 of Fig. 2.

Fig. 4 is a side elevation of the machine as viewed from the right side thereof.

Referring further to the drawings, the machine is provided with a base consisting of longitudinal members 1 and 2 and transverse members 3 and 4 connected rigidly together to form a rigid base. To the cross members are attached suitable feet, any one of which may be designated as 5. Side frame plates 6 and 7 are secured to the longitudinal base members and support between them the drum and other operative portions of the mechanism.

The drum itself is generally cylindrical, being formed of a sheet of metal 8 secured to end walls 9 and 11, the longitudinal edges of the sheet of metal being bent inwardly at the flanges 12 and 13, thereby leaving a gap of considerable arcuate width extending the full length of the drum be- 50 55

tween its end walls. On this drum a duplicating band made of gelatin or some other suitable material may be positioned.

When a gelatin band is employed, it will ordinarily have a hook member 14 which may be engaged over the edge of the flange 13, while the other end of the band will be provided with a similar hook member to be engaged by a tensioning device. The latter is in the form of a plate 15 secured to a rod 16 which is pivotally mounted in the opposite end walls of the drum. Rigidly connected with the rod and plate 15 for rotating the same is another rod 17 connected by rigid arms to the rod 16, one of these arms being indicated as 18 in Fig. 1. Formed integrally with each of the arms 18 at opposite ends of the rod 16 are depending flanges such as 19 to which may be connected springs such as 21 secured to the inside surfaces of the drum end walls for normally rotating the duplicating band tensioning device into the interior of the drum.

To attach the duplicating band to the drum, the channel-shaped hook 14 on one end of the band is engaged over the flange 13. The band is 25 then carried around the drum and the tensioning member is grasped by the handle rod 17, rotated outwardly from the drum gap against the action of springs 21 far enough so that the hook 22 on the other end of the band may be engaged over the plate 15. The springs will then be permitted to rotate the tensioning device back toward its normal position, thereby stretching the band tautly over the drum surface.

The duplicating drum itself is carried on a shaft 23 which is journalled in bearings 24 and 25 supported in the side frame plates 6 and 7. The operating handle 26 is rigidly secured to the right-hand end of the shaft 23. If a motor drive should be employed, it could be connected to the 30 35 40 shaft in place of the handle.

Referring to Fig. 3, the drum end wall 9 is secured by means of rivets to a gear 27 and also to a bushing 28, the latter riding freely on the shaft 23, so that the drum and shaft are free to rotate relatively to each other. The gear 27 is employed to drive a gear 29 secured to the shaft 31 of a rubber stripping roll 32.

The opposite end wall of the drum is supported on bushing 33 in which the drum shaft is free to rotate. A plate 34 is fixed on the bushing 33 against the enlarged portion 35 of the bushing, the plate or disk 34 being screwed, riveted or welded to the drum end wall. Between the bearing 25 in which the shaft rotates and the bushing 33 and its enlarged portion 35,

is another bushing 36 pinned to the shaft and carrying fixed thereon a cam disk 37. The periphery of this cam actuates the automatic paper feed, as will be described later.

Secured to the side frame plate 7 in a slightly spaced relation by means of screws 38 and washers 39 are a pair of stationary plates, best shown in Fig. 2, and there designated as 41 and 42, which are shaped to provide between the outer margin of plate 42 and the inner margin of plate 41, a cam groove which is employed in the interrupted drive of the duplicating cylinder.

Cooperating with the cam plates 41 and 42 is a bell crank pivotally mounted in the cam disk 37 on the pivotal axis 43 and comprising a pair of bell crank arms 44 and 45, the latter arm carrying a cam follower 46 pivotally mounted on the arm on ball bearings and engaged in the cam groove between the plates 41 and 42. The other bell crank arm 44 pivotally carries a square head 47 which is adapted for sliding movement in a rectangular slot 48 in the plate 34.

The cam disk 37 which is non-rotatably mounted on the shaft 23 by means of the keyed bushing 36 drives the bell crank and the bell crank drives the drum through the arm 44 and plate 34. However, when the shaft 23 is being rotated manually or by motive power at a uniform speed, the speed of rotation of the drum will be varied in accordance with the motions of the bell crank induced by the cam follower 46. If the cam follower 46 traveled in a perfectly circular cam way concentric with the axis of the drum shaft, the drum and shaft would always move at the same speed. While the shaft is rotating at a uniform speed, and consequently the pivotal axis 43 is moving at the same uniform speed, whenever the cam follower 46 tends to approach the axis of the shaft, the opposite end of the bell crank will be rotated in a direction counter to the direction of rotation of the shaft, thereby retarding the speed of rotation of the drum. Conversely with the cam follower and receding from the shaft axis, the square head carried by the opposite end of the bell crank will accelerate the drum relatively to the shaft. Accordingly, the cam way formed by the plates 41 and 42 is so designed that in a portion of the cam way the deceleration of the drum caused by the radially inward movement of the cam follower 46 is caused to offset the forward motion of the bell crank axis 43, whereby for a short time during the rotation of shaft 23, the drum will be standing still.

The cam way and the bell crank are so designed and positioned relatively to each other that the drum is caused to stop while the shaft continues to rotate when the parts are occupying the position shown in Fig. 1, at which time it will be noted that the margin bar 49 has been rotated to a position underneath the pressure roller 51, the feeding position for copy sheets. According to the design shown, after the drum has been rotated to bring the margin bar to the position shown in Fig. 1, the drum shaft can be rotated in the neighborhood of an additional 50° before the drum will resume rotating. This interval is ample time for the sheet feeding mechanism, or a manual feeding operation to feed a copy sheet snugly up against the margin bar as shown in Fig. 1.

It will now be apparent that the length of the interval may be varied by a change of design of the cam and the cooperating parts. In fact, since the inward rotation of the bell crank arm 45 tends to rotate the drum rearwardly while

the forward movement of the pivotal axis 43 tends to rotate the drum forwardly, it is possible to have the effect of the inward movement of the arm 45 greater so that the drum could be rotated rearwardly a short distance. Also, the parts could be so designed that the effect of the inward movement of the bell crank arm 45 would not quite offset the forward propelling effect of the motion of the pivotal axis 43. Hence, the design could be so arranged as to cause the drum to move forwardly at all times but slowly for part of the revolution. It will be perceived that when the arm 45 is swinging radially outwardly and the bell crank axis 43 is moving at a uniform speed, the drum will be propelled by the bell crank at a higher rate of speed than the shaft is then rotating.

Normally, this mechanical movement is useful in temporarily stopping the drum in the duplicating machine herein shown, but it may be used for a similar purpose or for generally varying the relative speeds between the drive means and the drum in any duplicating machine.

The margin bar heretofore referred to, is mounted on a pivoted deflector plate generally indicated as 52 supported on a rod 53 journaled in the drum end walls. An extension 54 from the flange 13 forms an anchor for a spring 55 which may be connected to a downwardly extending center leg 56 on the deflector plate, tending normally to rotate the edge portion 57 of the deflector plate outwardly a slight distance beyond the peripheral surface of the drum, excepting when the deflector is held down by the pressure roller 51. The extent to which this deflector may rotate outwardly is limited by the contact of a leg 58 depending from deflector 52 with a bumper 58' provided on a plate 59 likewise pivoted on the rod 53. The extent to which the pressure roller may press the deflector 52 inwardly is limited by contact of a leg 60 depending from deflector 52 with an eccentrically pivoted adjustable button 60'. A spring 61 connected to the opposite end of the plate 59 and anchored on the inside surface of the adjoining drum and wall tends normally to hold the plate 59 against an eccentrically pivoted adjustable button 63.

To attach the end of a gelatin band to or remove it from the flange 13, one needs only to press on the center leg 56, causing leg 58 to press on the bumper 58' to rotate the whole unit including the plate 59 far enough to provide a large gap between the edge of the deflector and the shoulder of the flange 13.

To advance copy sheets from a stack on the feed table 64, there is provided a feed mechanism consisting of an arm 65 pivoted on a post 66 carried by the side frame plate and provided at its opposite end with a follower 67 which follows the cam 31. A link comprising two members 68 and 69, the latter carrying a post 71 and the former a post 72 connected by a tension spring 73, forms a resiliently extensible link for transmitting cam motion to a bell crank 74 fixed on a rod 75 on which is fixed another duplicate bell crank, the two of which operate a friction feeding shoe 76 fixed on the end of an arm 77 pivotally mounted on a cross rod 78 carried at the upper ends of the pair of bell cranks. As the high point on the cam 31 is reached, as shown in Fig. 1, the feeding shoe is moved forwardly by the pair of bell cranks and frictionally engages the top sheet on the stack to slide it underneath the guide plate 79 up against the margin bar 49.

Continued rotation of the shaft 23 by means of the handle 26 or by motive power will eventually move the margin bar 49 out from underneath the pressure roller 51 whereupon the latter will press the copy sheet first against the deflector plate 52 and thereafter against the duplicating band 81 to receive the copy therefrom.

The stripping of a copy sheet is accomplished as follows. After the deflector plate passes from underneath the pressure roller, it will be deflected a short distance outwardly by the springs 55 causing the overlying edge of the copy sheet likewise to be deflected outwardly from the periphery of the drum. As this deflected portion comes around to the position of the stripping plate 82, it will be engaged thereby and caused to pass between the rubber roller 32 and another roller, preferably a knurled metal roller 83. The latter roller may be an idler, whereas the rubber roller 32 is positively driven by the gear 27. The sheet will thereby be stripped from the duplicating band, guided by the plate 84 and dropped into the delivery chute 85 with the printed side up.

The pressure roller 51 heretofore mentioned, is mounted on a shaft carried between a pair of arms 86 and 87 pivoted at 88 and 89, the arms being held downwardly by springs, one of which is shown in Fig. 4 and is numbered 91. The idling stripping roll 83 is likewise carried on a shaft journaled in a pair of arms 92 and 93 mounted outside of the main side frame plates, each arm being held under tension by springs such as 94. Any other suitable means for supplying adjustable pressure on these two rollers may be employed.

The feed table herein illustrated is provided with adjustable side plates such as 95 and 96 through which may protrude elements such as pads for engaging the sides of the stack of copy sheets.

In the operation of the device, the handle may be continuously operated, the drum stopping, as explained heretofore, for a short interval with the margin bar underneath the pressure roller 51. At this time, the automatic feeding mechanism will advance a copy sheet with its leading edge against the margin bar, or this may be done manually. Further rotation of the handle will cause the drum to resume rotating, after which the copy sheet will be pressed against the duplicating band and subsequently stripped as heretofore explained.

It should be understood that the embodiment herein shown and described, is merely illustrative of one form of the invention and that other forms and modifications of the whole and its parts may be devised and employed without departing from the spirit and scope of the invention, particularly as it may be defined in the appended claims.

Having shown and described my invention, I claim:

1. In combination with a duplicating machine having a rotary master copy drum, a mechanism for imparting intermittent rotary motion to the drum comprising a continuously rotating driving member, an element pivotally connected with said member and driven thereby through the pivot, one end of said element being connected to the drum for driving the same, and means for rotating the element about its pivotal axis during the circular travel of said axis whereby during a portion of said travel no rotative motion will be imparted to said drum,

2. In a duplicating machine, a rotary master copy drum, a rotary driving member, a driving element pivotally mounted on said member at a position spaced from the axis of said member, means connecting one end portion of said member with the drum to thereby impart rotary motion to the drum, and means for rotating said element about its pivotal axis while said axis is continuously moving in a circular path for varying the relative rotative speed of said drum and said driving member.
3. In a duplicating machine, a rotary master copy drum, a rotary driving member, a driving element pivotally mounted on said member at a position spaced from the axis of said member, means connecting one end portion of said member with the drum to thereby impart rotary motion to the drum, and means for rotating said element about its pivotal axis while the latter is continuously moving in a circular path for varying the speed of the drum relatively to that of the driving member from equality to zero.
4. In combination with a duplicating machine having a rotary master copy drum, an intermittent driving mechanism therefore comprising a continuously rotating driving member, an element pivotally carried by said member and having its pivotal axis moving continuously through a circular path, means connecting said element with the drum for driving the latter, and means operating during the continuous movement of said pivotal axis to rotate said element about its pivotal axis in a direction opposed to the rotation of said driving member whereby for an interval no rotative movement is imparted to the drum.
5. In a duplicating machine having a rotary master copy drum, a rotary driving member, a pivoted element driven by said driving member, one end of said pivoted element being operatively connected to the drum for rotating the same, a cam, and the other end of said element being arranged to follow said cam to rotate said pivoted element about its axis to thereby vary the relative rotative speeds of the drum and said driving member.
6. In a duplicating machine having a rotary drum for carrying master copies, means for driving the drum including a continuously rotating driving member, an element pivotally carried by said member, one end of said pivoted element being operatively connected to the drum for driving the same, and a cam, the other end of said element being controlled by said cam for rotating the whole element on its pivotal axis for varying the speed of rotation of the drum relatively to the driving member.
7. A duplicating machine having a rotary master copy drum and a copy sheet margin stop carried by the drum, and a driving mechanism for intermittently rotating the drum and stopping it with the margin stop at the feeding position comprising a continuously rotatable primary driving member, an element pivotally carried by said member and pivoted between its ends, one end of said element having an operative connection with the drum to transmit rotated movement thereto, and means acting on the other end of said element for rotating said operative connection about the pivotal axis of the element in opposition to the travel of said pivotal axis for intermittently stopping the drum.
8. A duplicating machine having a rotary master copy drum and a copy sheet margin stop carried by the drum, and a driving mechanism for

intermittently rotating the drum and stopping it with the margin stop at the feeding position comprising a continuously rotatable primary driving member, an element pivotally carried by said member and pivoted between its ends, one end of said element having an operative connection with the drum to transmit rotative movement thereto, means acting on the other end of said element for rotating said operative connection about the pivotal axis of the element in opposition to the travel of said pivotal axis for intermittently stopping the drum, and means actuated by the rotation of said driving mechanism arranged to automatically feed the copy sheets to said margin stop when the drum is stationary.

9. In a duplicating machine having a rotary master copy drum, a rotary shaft, a rotary member driven by said shaft, an element pivoted between its ends on said member to rotate bodily therewith, an operative connection between one end of said element and the drum for rotating the latter, and stationary cam means cooperating with the other end of said element for rotating said element about its pivotal support to vary thereby the relative rotative speeds of the drum and said shaft.

10. In a duplicating machine having a rotary master copy drum, a rotary shaft, a rotary member driven by said shaft, an element pivoted between its ends on said member to rotate bodily therewith, an operative connection between one end of said element and the drum for rotating the latter, and stationary cam means cooperat-

ing with the other end of said element for rotating said element about its pivotal support to vary thereby the relative rotative speeds of the drum and said shaft, said cam and element being constructed and arranged to cause the drum to stop at the copy sheet feeding position during part of the continuous rotation of the shaft.

11. In a duplicating machine, a rotary master copy drum, a drive shaft, an arm fixed on said shaft to rotate concentrically therewith, an element pivotally supported between its ends on said arm at a point spaced apart from the axis of rotation of said arm, means slidably connecting one end of said element with the drum for rotating the latter, means for oscillating said end of said element about its pivotal axis during rotation of the shaft to vary the relative speed of rotation of the shaft and drum.

12. In a duplicating machine, a rotary drum, a continuously rotating shaft concentric with the drum, an element pivotally carried by said member and continuously driven at its pivotal point along with said shaft, one portion of said element being operatively connected with the drum to propel the same, a cam follower on another portion of said element, means providing a stationary cam way cooperating with said follower to pivotally rotate said element to hold the drum stationary during a portion of the rotation of said shaft, and means for feeding copy sheets to the drum for accurate registration therewith while the drum is stopped.

WILLIS A. KROPP.
